UNITED STATES PATENT OFFICE.

STEVEN PALC AND EDWIN G. BOSTWICK, OF KALAMAZOO, MICHIGAN.

TRAIN-CONTROL MEANS.

Application filed May 18, 1921. Serial No. 470,659.

To all whom it may concern:

Be it known that we, STEVEN PALC and EDWIN G. BOSTWICK, citizens of the United States, residing at the city and county of 5 Kalamazoo, State of Michigan, have invented certain new and useful Improvements in Train-Control Means, of which the following is a specification.

This invention relates to improvements in 10 train control means.

The main objects of this invention are:

First, to provide an improved means for automatically stopping a train by setting a 15 semaphore or other tripping means at the side of the track.

Second, to provide an improved train control means which is not likely to get out of repair or become inoperative.

Further objects, and objects relating to 20 structural details, will definitely appear from the detailed description to follow.

We accomplish the objects of our invention by the devices and means described in the following specification. The invention is 25 clearly defined and pointed out in the claims.

A structure which is a preferred embodiment of our invention is clearly illustrated in the accompanying drawing, forming a part of this application, in which:

30 Fig. I is a side elevation of a locomotive on the track equipped with our improvements, the parts being shown mainly in conventional form.

Fig. II is a transverse section on a line 35 corresponding to line 2—2 of Fig. I.

Fig. III is an enlarged detail view of one of the trip members on a line corresponding to line 3—3 of Fig. II.

Fig. IV is a detail or fragmentary plan view showing details of the operating connections.

Fig. V is a detail view partially in vertical section on a line corresponding to line 5—5 of Fig. II, showing further details of 45 the operating connections.

Fig. VI is a fragmentary view partially in section on a line corresponding to line 6—6 of Figs. I and II, showing details of the operating connections from the 50 semaphore to the second trip member.

In the drawing similar reference characters refer to similar parts throughout the several views, and the sectional views are taken looking in the direction of the little 55 arrows at the ends of the section lines.

Referring to the drawing, 1 represents a

railway locomotive, 2 the rails, and 3 the ties. The air pipe of the brake system is represented at 4. In this system we install valves 5 and 6, the valves being arranged so 60 that when opened they set the brakes.

7 represents the brake valve in control of the engineer.

The valve 6 is operated through the tappet lever 8 pivotally mounted on the under side of the running board 9 of the locomotive and connected by the link 10 to the valve 6. A second tappet lever 11 is mounted on a hanger 12 to project downwardly, this lever being connected by the link 13 to the valve 5. At the side of the track is a semaphore 14 having a swinging arm 15 adapted when swung to erected position to engage the tappet lever 8 as the locomotive passes the semaphore. This semaphore arm 75 is controlled from the rock shaft 16 having a bell crank 17 thereon, one arm of which is connected to the semaphore arm by the link 18, the operating rod 19 being connected to the other arm. This operating rod 80 is extended to the tower or other signal station point.

We provide a trip member 20 to coact with the trip lever 11, the trip member 20 being mounted to reciprocate in the housing 21, which is mounted between a pair of the ties 3, so that when the trip member is projected it is in position to engage the lever 11. The trip member 20 is provided with a rack 22 actuated from the gear 23 disposed within the housing, the gear being driven from the segment 24 having an arm 25 thereon. This arm 25 is connected by the link 26 to an arm 27 on the rock shaft 16, the rock shaft 16 being provided with 90 a housing 28 and the link 26 with a housing 29. A housing 30 is provided for the arm 27 on the rock shaft.

With this arrangement, the trip and the semaphore may be at considerable distance. 100 They are shown in the accompanying drawing relatively close together in order that the cooperating relation of the parts with the tappets on the locomotive might be illustrated.

Our improved control means are automatically set by the setting of the semaphore. Two control means are provided which may be set simultaneously, thereby lessening the possibility of failure in stopping the 110 train.

We have illustrated and described our

improvements mainly in conventional form, but we believe in sufficient detail to enable those skilled in the art to embody our improvements as circumstances may render desirable.

Having thus described our invention, what we claim as new and desire to secure by Letters Patent, is:

1. An apparatus for stopping trains equipped with air brake systems having embodied therein a pair of control valves and operating means therefor comprising independent tappet levers, a semaphore arm disposed at the side of the track so that when actuated it is in position to coat with one of said tappet levers, a gear box trip member housing mounted at one side of the track, a trip member mounted in said housing to project therefrom when actuated to coat with the other of said tappet levers, an operating means for said semaphore, and operating connections therefrom to said trip member.
2. An apparatus for stopping trains equipped with air brake systems having

embodied therein a pair of control valves and operating means therefor comprising independent tappet levers, a semaphore arm disposed at the side of the train track so that when actuated it is in position to coat with one of said tappet levers, a gear box trip member housing mounted at one side of the track, a trip member mounted in said housing to project therefrom when actuated to coat with the other of said tappet levers, an operating means for said semaphore, and operating connections therefrom to said trip member.

3. An apparatus for stopping trains equipped with air brake systems having embodied therein a pair of control valves and operating means therefor comprising independent tappets, a semaphore arm disposed so that when erected it is in position to coat with one of said tappets, a trip member mounted on the track to coat with the other tappet, means for actuating said semaphore, and operating connections therefrom to said trip member.

In witness whereof we have hereunto set our hands and seals in the presence of two witnesses.

STEVEN PALC. [L.S.]
EDWIN G. BOSTWICK. [L.S.]
